UNITED STATES PATENT OFFICE

142,096

DESIGN FOR A COMBINATION OF COSTUMER AND SHELF UNIT OR SIMILAR DEVICE

Benjamin E. Levin, Boston, Mass.

Application January 1, 1945, Serial No. 117,212

Term of patent 7 years

(Cl. D80—8)

To all whom it may concern:

Be it known that I, Benjamin E. Levin, a citizen of the United States, residing at Boston, in the county of Suffolk and State of Massachusetts, have invented a new, original, and ornamental Design for a Combination of Costumer and Shelf Unit or Similar Device, of which the following is a specification, reference being had to the accompanying drawing, forming a part thereof.

The figure is a perspective view of a combination of costumer and shelf unit or similar device showing my new design.

The other side of the figure is substantially the same as that shown.

I claim:

The ornamental design for a combination of costumer and shelf unit or similar device, substantially as shown and described.

BENJAMIN E. LEVIN.
